UNITED STATES PATENT OFFICE.

BERTHOLD JAHN AND ERNEST EMIL KAHL, OF NEW BRITAIN, CONNECTICUT, AS
SIGNORS TO THE B. JAHN MANUFACTURING COMPANY, NEW BRITAIN, CONNECTI-
CUT, A CORPORATION.

STAPLE BINDER.

Application filed November 25, 1916, Serial No. 133,357. Renewed February 23, 1921. Serial No. 447,224.

To all whom it may concern:

Be it known that we, BERTHOLD JAHN and ERNEST EMIL KAHL, citizens of the United States, residing at New Britain, in the county of Hartford and State of Connecticut, have invented certain new and useful Improvements in Staple Binders, of which the following is a specification.

Our invention relates to improvements in staple binders, and the object of our improvement is simplicity and economy in construction and convenience and efficiency in use.

In the accompanying drawing:

Figure 1 is a side elevation of our improved staple binder.

Figure 2 is a plan view of the same.

Figure 3 is a bottom view of the same.

Figure 4 is a side elevation, on an enlarged scale, of the same with one of the side plates removed.

Figure 5 is a similar view with the parts in a different position.

Figure 6 is a side elevation of the die member.

Figure 7 is a plan view of the same.

Figure 8 is an end elevation of the same.

Figure 9 is a sectional view, on an enlarged scale, on the line $\alpha\alpha$ of Fig. 7.

Figure 10 is a sectional view on the line yy of Fig. 13.

Figure 11 is a sectional view on the line uu of Fig. 3.

Figure 12 is a sectional view on a still further enlarged scale, on the line vv of Fig. 5.

Figure 13 is a view corresponding to Figs. 4 and 5, with the parts in a different position, being on the same scale as the said Figs. 4 and 5.

Figure 14 is a bottom view, in part broken away, on the same scale as Fig. 12, of a modification of the die member.

Figure 15 is a sectional view on the line ss of Fig. 14.

Figure 16 is a sectional view on the line tt of Fig. 14.

Figure 17 is a plan view on the same scale as Figs. 4 and 5, of a portion of the blank for one of the side frame members.

Figure 18 is a perspective view, in part broken away, of a portion of one of the staple strips.

Figure 19 is a side elevation on a reduced scale of a modification of our improved staple binder.

Figure 20 is a bottom view of the same.

Figure 21 is a fragmentary sectional view on an enlarged scale on the line zz of Fig. 20.

Figure 22 is a similar view of a modified form of construction.

Figure 23 is a view generally similar to Fig. 13 with the pawls in the raised position relatively to the anvil member.

Figure 24 is a plan view of the blank for the holding pawl shown in Fig. 23.

Figure 25 is a similar view of the feeding pawl.

Our improved staple binder comprises a base 10 having adjacent one end an anvil 11, and a frame 12 hinged to the base 10 adjacent the other end as shown at 13, and mechanism housed in the said frame 12 for operating on staples 14 supplied in strip form and inserted in the said frame. The said mechanism serves to sever individual staples from the said strip, and to drive and clinch the said individual staples, and comprising a plunger member 15 for cooperating with the relatively stationary die 16 and with the anvil 11.

The base 10 is formed of sheet metal, pressed into shell-like form so as to form a central platform 17 bordered by flange-like side walls 18 extending around the edges. At the anvil end the platform 17 is further pressed upwardly to form the anvil 11 and the said anvil 11 is provided with a pair of curved depressions 19 that register with the points of the staples for turning the said points and effecting the clinching in cooperation with the plunger member 15.

At the end remote from the anvil 11 the platform 17 is provided with a pair of slits in which are housed the upwardly projecting arms 20 of a U-shaped pivot support 21, the yoke portion 22 connecting the said arms 20 being positioned in face to face contact with the under side of the platform 17 and secured in such position by means of a rivet 89.

The arms 20 are provided with holes for the pivotal pin 13.

The die member 23 has one end positioned between the arms 20 and has a hole for the

pivotal pin 13, and thereby serves to provide the pivotal connection between the frame 12 and the base 10.

The die member 23 is in the form of an 5 elongated block extending from the point of pivotal connection to adjacent the anvil 11, being of suitable length to receive a staple strip of appreciable length, and has the upper portion recessed at the sides as 10 shown at 24, Fig. 10, to provide a fit for the under side of the said staple strip.

A plurality of studs 64, shown as two in 15 number, are positioned in the lower portion of the die member 23, the laterally projecting ends of which register with holes in the two side frame members 25, and a hole 26 is provided adjacent the die 16 for receiving a screw 27 that serves to hold the side frame members 25 in place and also as a die clamping 20 screw in a manner to be described.

The die 16 is of peculiar form, as shown, having a conical head 31 at the upper end, the large end being uppermost, a part of the circular upper edge portion of which 25 serves as the stationary cutting edge. The die member 23 is provided with means for housing the said die 16 and permitting of rotating the same to change the part that serves as the die proper or active portion.

30 The said means comprise a split in the end portion of the die member 23 formed by a longitudinal slot 32, terminating at the outer end in a bed 90 that fits the die 16.

The said die 16 comprises the conical 35 tapered head 31 at the upper end terminating in an annular shoulder 33 that serves as a base, and a stem 34 that extends downwardly from the base 33 through the die member 23, the lower face being provided 40 with a slot 35 suitable for receiving a screw-driver for turning the die 16 to the position desired.

The outer portion of the head 31 overhangs slightly the adjacent end face 36 of 45 the die member 23 as shown at 37.

Thus the die end of the die member 23 is divided to form two opposed arms 38, the ends of which are recessed to bear against the sides of the die 16, the said arms 38 being adapted to be clamped against the die 16 by the screw 27, already mentioned, and thereby hold the die in the adjusted position. As mentioned, the screw 27 serves 50 to hold the two side frames 25 in place on opposite sides of the die member 23 and also effects the holding of the die 16 in the adjusted position, and the particular manner of doing this as shown is as follows:— the hole 91 in the left side frame member 25 55 that is opposed to the head 92 of the said screw 27, is a clearance hole for the body of the said screw, as is also the hole 26 in the die member 23, the said hole 26 being continued through the two clamping arms 60 65 38, and the hole 93 in the right side frame

member 25 is a threaded hole, as shown in Fig. 12 that is engaged with the threaded end of the screw 27. Thus the arms 38 are clamped between the two side frame members 25.

The plunger 15 is a vertically positioned 70 block, having a handle 40 at the upper end, and recesses 41 extending along the lateral faces for engaging with guide flanges 42 on the frame members 25, that operatively 75 position the plunger adjacent the end of the die member 23. A spring 43, enclosing the upper end portion, and bearing by its 80 ends against the said handle 40 and the frame members 25, tends to hold the said plunger 15 in the uppermost position.

The lower end face 94 of the plunger 15 is flat and the face opposed to the end of the die member 23 is generally flat to fit 85 against the end face 36 of the said die member 23 and at the middle is provided with a longitudinally extending groove 39 (Fig. 12) that fits against the cutting edge 37.

Thus the end face 94 of the plunger 15 serves as the moving shearing die and also 90 as the hammer for driving and clenching the staples 14.

The plunger 15 is provided on the inner 95 face with an inwardly projecting wing 44 that cooperates with the internal mechanism housed in the frame 12, comprising an inwardly directed finger 45 at the lower end and a shank portion 46 extending upwardly from the said finger 45 and terminating at the upper end suitably to serve as 100 a stop in cooperation with the opposed portion 47 of the frame 12 to limit the upward movement of the plunger 15.

The said interior mechanism comprises a holding pawl 48, a feeding pawl 51, and a 105 dog 52. The said holding pawl 48 is pivotally mounted on the frame 12 by means of a pivotal pin 49 and is held in operating position by means of a spring 50 suitably to prevent return movement of the staple 110 strip by engaging with one of the staples 14.

The feeding pawl 51 is pivotally mounted 115 on the dog 52 by means of a pin 53 and is furthermore operatively connected with the dog 52 by means of a spring 54 that tends to open out or spread apart the said dog 52 and pawl 51.

The dog 52 is pivotally mounted on the frame 12 by means of the pin 55, and besides 120 serving as a supporting member for the feeding pawl 51 is formed so as to provide at the rear portion a lug 56 that engages with the opposed portion 57 of the back wall of the frame 12, said back wall being composed of opposed flanges 58 of the 125 frame members 25.

On the side opposed to the wing 44 on the plunger 15 the dog 52 comprises an outwardly directed lug 59 for engaging with the lug 45 on the plunger 15 and below the 130

said lug 59 the edge portion is in the form of a cam face 60 that extends downwardly in a straight line, suitably for engaging with the opposed end face of the lug 45 5 on the plunger 15, and thereby position the dog 52 and the feeding pawl 51 during the downward travel of the plunger 15, as shown in Fig. 5.

With the plunger 15 in the position, as 10 shown in Fig. 4, the staple strip serves to position the feeding pawls 51. In this position both pawls 51 and 48 are engaged with the staple 14 next to the end one which is positioned in the channel 61 between the 15 guide flanges 42 of the frame and the end face 36 of the die member 23.

During the downward movement of the plunger 15 the feeding pawl 51 is brought to the position shown in Fig. 5 suitable for 20 engaging with the next staple 14 and feeding the staple strip along when the plunger 15 is again elevated. Such forward movement is positively effected by the lug 45 engaging with and lifting the lug 59.

25 The forward feeding movement of the staple strip is limited by the end staple 14 coming in contact with the guide flanges 42 of the frame. In this position the portion of the connecting neck that connects the adjacent 30 staples 14 that projects beyond the staple is positioned in the open space between the opposed edges of the guide flanges 42.

As described, the forward feeding movement of the feeding pawl 51 is under normal 35 conditions of operation limited by the intervening portion of the staple strip, consisting of two individual staples, and the neck 62 connecting the same.

In case, however, there is no staple strip 40 in the machine the feeding pawl 51 is carried a little forward of such normal forward position and may be carried to the edge of the die member 23, as shown in Fig. 15.

Under these conditions the dog 52 is free to 45 move away from the lug 45 and the forward movement is limited by checking the rotative movement of the dog 52 by means of the upper frame screw 63 that engages with the edge of the dog 52, the said screw thus 50 serving as a stop and also as one of the screws for holding the side frame members 25 in place.

This feature of the operation serves to effect the ejection of the last staple 14 of 55 the staple strip immediately after the next to the last staple has been cut off and operated upon, and thereby prevents the clogging of the machine by the said last staple.

To consider this feature in further detail 60 with the binder charged with a staple strip and ready for use, with the parts in the position shown in Fig. 4, and counting from the end opposed to the guide flanges 42,

the holding pawl is always in position to 65 engage with and hold the second staple

from the end and the feeding pawl is engaged with the said staple. As the plunger descends the first staple is cut off, the second staple is held from moving rearwardly by the holding pawl, and the feeder pawl is 70 brought to the rearmost position, shown in Fig. 5, which is slightly to the rear of the third staple, suitably to engage with the said third staple when free to do so. After the end staple has been driven and the 75 plunger is lifted the feeding pawl engages with the said third staple and moves the staple strip forward so that the said third staple is positioned in place of the previous second staple. When however the condition 80 has been reached when only two staples remain of the staple strip, after the end staple, opposed to the guide flanges has been severed and operated upon in the usual manner, upon the elevation of the plunger 85 the ejection of the last staple by delivering the same to the channel 61 is effected by the feeding pawl. The said feeding pawl is moved freely past the space usually occupied by what is initially the third staple, and 90 also is moved beyond the usual checking position to the final checking position mentioned above and shown in Fig. 13, and in this movement carries with it the last staple, thus carrying the same positively 95 into the said channel 61.

The side frame members 25 that comprise the frame or casing, are formed of sheet material of generally triangular form, the body portions having holes for engaging 100 with the studs 64 and other holes for a set of frame screws comprising the clamping screw 27, and the upper frame screw 63, already mentioned, and a third screw 65 adjacent the pivotal connection.

The top edge portions are turned inwardly to form the flanges 58 that meet to form the back wall.

The front edges are vertical and for the greater part of the length are turned inwardly to form the guide flanges 42. Above the guide flanges 42 the blank is provided with a laterally extending finger 66 that is curled around the outer face of the plunger 15 to form an extension of the platform 67 115 that supports the lower end of the main spring 43.

As the guide flanges 42 are directed inwardly relatively to the body portion of the side frame members 25, the said guide 120 flanges are positioned opposite the end of the die member 23 and in line with the finger portions of the staple strip mounted on the die member 23, and are accordingly positioned suitably to serve as a stop for 125 the said staple strip as the same is fed along the operating mechanism as has been described.

In the modification shown in Figs. 14, 15 and 16 the die member 23^a is formed of sheet 130

material, being composed of a main part 68 and a reinforcing part 69. The main part 68 is formed of a long strip, bent upwardly transversely into generally U-shape, with 5 an off-set as shown at 70, at about the middle portion, whereby the top part 71 is slightly narrower than the base part 72, and recesses 24^a are provided for housing the fingers of the staple strip.

10 The reinforcing part 69 is of U-shape of cross-section and fits in the interior of the base part 72.

15 The die 16^a is set in the die member 23^a in the same manner generally as in the single piece die member 23 described, it being noted that the head portion 31^a of the die 16^a extends sufficiently downwardly so that the base portion 33^a rests on the reinforcing member 69.

20 While we have shown the cutting edge portions of the dies 16 and 16^a as circular, we may in some cases provide an octagonal or other polygonal form therefor, whereby a straight active cutting portion may be obtained with a proper adjustment of the die, and the die may be turned to present the different sides as desired.

25 In the modification shown in Fig. 19 the staple binder is provided at the bottom with a pair of base strips 73 in spaced relation, there being one at each end of the base 10^b, that serve as feet and also there is provided a handle 74 in the form of a thumb piece projecting through a recess 75 in the rear wall 58^b of the frame 12^b that serves when moved away from the normal position by being depressed by the thumb to lift the pawls and release the staple strip so that the same can be moved back and forth along 40 the die block 23 as desired.

30 The base strips 73 are formed of a strip of sheet material, comprising the body portion extending transversely across the base 10^b, and ends 76 turned up against the inclined base flanges 18^b and having at each end a lug 77 that is turned into a hole 78 in the said side flange 18^b.

35 The ends 76, because of their angular or inwardly inclined position relatively to the body portion, serve generally as the means for connecting the base strips 73 with the base 10^b and the interengagement of the lug and hole described locks the same against longitudinal movement.

40 In the modification shown in Fig. 22 the end 76^c is provided with a hole 78^c to receive a lug 77^c in the form of an indentation of the sheet material of the base flange 18^c.

45 In the modification shown in Fig. 23 means are shown for lifting the pawls comprising a handle 74 projecting through the rear wall of the frame or casing.

50 The handle 74 is in the form of a rearward extension of the holding pawl 48^a, the construction of the same being otherwise simi-

lar to the pawl 48, and the feeding pawl 51 being unchanged.

Both pawls are made of sheet material.

55 The blank for the holding pawl 48^a is shown in Fig. 24 and comprises a longitudinally extending body portion 79 having at one end a pair of tooth shaped wings 80, one on each side, that are turned downwardly to form the holding teeth, having the handle 74 at the other end, and intermediate the 75 said ends having a pair of side wings 81 that are turned upwardly to form a channel in which the spring is housed and having holes 82 for the pivotal pin.

60 The blank for the feeding pawl 51 is shown in Fig. 25 and comprises a pair of side wings 83 having pivot holes 84 at one end, connected together adjacent the said end by a narrow connecting strip 85, the other ends being separated by a space 86. The side 85 wings 83 are bent upwardly relatively to the connecting strip 85 so as to form a channel structure, the spring 54 bearing on the connecting strip 85. The ends 87 remote from the pivotal holes 84 serve as 90 the feeding teeth, and these are spaced so as to be positioned outside of the teeth 80 by providing an off-set bend in the wings 83 as shown at 88, adjacent the teeth 87. In use, the feeding pawl 51 is positioned generally above the holding pawl 48^a, the body portion 79 of the latter extending along between the teeth 87 and below the relatively narrow channel structure adjacent the off-set bends 88. Therefore, as the handle 74 100 is manipulated so as to raise the holding pawl 48^a as the movement is continued the feeding pawl 51 is also raised and thereby the space between the pawls and the die block 23 is clear, and without obstruction 105 against freely moving a staple strip back and forth.

65 Thus means are provided for clearing the staple strip space on the die block or die member 23, a feature that is desirable for 110 use in charging the machine and also in case it is desired to remove or shift the staple strip for any reason.

70 It is apparent that some changes from the specific construction herein disclosed may 115 be made and therefore we do not wish to be understood to limit ourselves to the precise form of construction shown and described, but desire the liberty to make such changes, in working our invention, as may fairly come 120 within the spirit and scope of the same.

75 We claim as our invention:—

1. In a staple binder, a die member positioned between a pair of side frames, pivotally connected by one end to the base, and having a die at the other end, the lower portion of the said die member fitting between the said side frames, and the upper portion thereof having recesses at the sides suitably to receive a staple strip, and the 130

said die member being formed of two parts of sheet metal, one of the said parts being bent transversely into generally U-shape with an off-set in the side walls to provide 5 for the said recesses, and the other of the said parts being of U-shape and fitting and filling the said lower portion of the die member.

2. In a staple binder, a die member positioned between a pair of side frames, pivotally connected by one end to the base, and having a die at the other end, the lower portion of the said die member fitting between the said side frames, and the upper 15 portion thereof having recesses at the sides suitably to receive a staple strip, and the said die member being formed of two parts of sheet metal, one of the said parts being bent transversely into generally U-shape 20 with an off-set in the side walls to provide for the said recesses, and the other of the said parts being of U-shape and fitting and

filling the said lower portion of the said one part, the said die member having a bed for a die of generally conical form, and the said die member having means for adjustably holding the die for permitting of changing the active cutting edge portion. 25

3. In a staple binder having a base and staple operating mechanism supported thereby, the said base being of shell-like form, and having inclined side flanges, a plurality of base-strips in spaced relation extending across the lower edges of the said flanges and having ends extending upwardly against 30 the said flanges, and catch devices for preventing relative longitudinal movement of the said base strips and side flanges. 35
